STOKER APPARATUS

Stuart H. Chapman, Lima, Pa., assignor to Westinghouse Electric Corporation, East Pittsburgh, Pa., a corporation of Pennsylvania

Application December 29, 1943, Serial No. 515,999

3 Claims.

This invention relates to furnace stokers, more particularly to those having overfeed grate sections inclined downwardly in the direction of fuel feed, and has for an object to provide improved inclined grate members of this character.

Another object of the invention is to provide, in an overfeed grate section, a grate surface inclined downwardly in the direction of fuel feed and including means for varying the angle of inclination of the fuel-supporting surface, whereby the optimum inclination for the particular fuel being used, may be obtained.

Another object of the invention is to provide grate bars of the inverted-V type, having a pivoted connection at the apex of the V, whereby the angle between the legs of the V may be varied to provide fuel-supporting surfaces inclined at the optimum angle for the particular fuel used.

These and other objects are effected by the invention as will be apparent from the following description and claims taken in connection with the accompanying drawing, forming a part of this application, in which:

Fig. 1 is a fragmentary plan view of a furnace stoker embodying the principles of the present invention;

Fig. 2 is a transverse elevational view showing a transversely reciprocable grate bar embodying the present invention; and,

Fig. 3 is a similar view of a stationary grate bar.

Referring to the drawing more in detail there is shown, at 10, a furnace installation embodying a furnace front wall 11 and side walls 12 and 13 which, together with the rear wall (not shown) form an enclosure for the grate structure 15. In the embodiment herein illustrated, the grate structure 15 is comprised by a plurality of transversely-extending grate bars of inverted-V configuration, the bars 16 being transversely reciprocable and the alternate bars 17 being stationary.

It will be apparent from consideration of Figs. 2 and 3 that the plurality of bars 16 and 17, assembled in side-by-side relation as indicated in Fig. 1, provide a pair of oppositely inclined fuel-supporting surfaces 18 and 19 extending downwardly in opposite directions from a common apex 20.

Fuel is fed from the hopper 21, through the opening 21a in the furnace front wall to the apex 20 of the grate surface, by the rotary impeller 21b.

For any given type of coal, fixed furnace width, and established grate surface, there is a most effective angle of the grate surface with respect

to the horizontal, of which the invention is designed to provide. This angle is determined by the characteristics of the fuel to be burned, the size of the grate, the size of the furnace, the size of the fuel feed, and the like factors.

It is an object of the invention to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

Another object is to provide a grate surface which may be inclined at an angle to the horizontal which will best suit the average of these fuels.

ceived in the notches 30 provided by the depending lugs 28 and 29 on the reciprocable bars.

To provide for raising or lowering of the apexes 20 of the reciprocable bars, a plurality of shims or spacing members 40 are provided between the members 38 and 39, it being obvious that addition or removal of a number of these shims will vary the height of the apexes 20 with respect to the stationary supports 22 of the grate bar ends, thereby providing for variation in the angle of inclination of the fuel-supporting surfaces 18 and 19 with respect to the horizontal.

In Fig. 3, there is illustrated one means for securing the stationary grate bars at any desired angular adjustment, this adjustment naturally conforming to that of the alternate reciprocable bars 16. The lower ends of the bars 17 likewise rest upon the stationary supporting plates 22 and preferably are provided with angle pieces 42, secured thereto by suitable means, such as the bolts 43. The under surface of the bars 17 may be provided with a plurality of openings 44 for reception of the bolts 43, in various positions of adjustment of the angle pieces 42.

While the invention has been shown in but one form, it will be obvious to those skilled in the art that it is not so limited, but is susceptible of various changes and modifications with-

out departing from the spirit thereof, and it is desired, therefore, that only such limitations shall be placed thereupon as are specifically set forth in the appended claims.

What is claimed is:

1. In a stoker, a plurality of grate bars of inverted-V type having pivotal joints at their apexes, means providing stationary supports for the ends of said bars, and means providing a transversely-movable support for the apexes of the bars.
2. Structure as specified in claim 1, wherein the transversely-movable support for the apexes of the bars is vertically adjustable with respect to the stationary supports, whereby the angle of inclination of the upper fuel-supporting surfaces of the bars may be varied.
3. A composite grate bar of inverted-V configuration providing a pair of upper fuel-supporting surfaces inclined downwardly in opposite directions from the apex, means carried by the bar for transmitting to the latter motion from a driving member, and means pivotally connecting the two legs of the bar at the apex thereof, whereby the inclination of the fuel-supporting surfaces may be varied.

STUART H. CHAPMAN.
